UNITED STATES PATENT OFFICE.

JOSEPH H. WEATHERFORD, OF MEMPHIS, TENNESSEE.

SANITARY CHAIR.

1,252,751.

Specification of Letters Patent. Patented Jan. 8, 1918.

Application filed June 10, 1916. Serial No. 102,917.

To all whom it may concern:

Be it known that I, JOSEPH H. WEATHERFORD, a citizen of the United States, residing in Memphis, in the county of Shelby 5 and State of Tennessee, have invented certain new and useful Improvements in Sanitary Chairs, of which the following is a specification.

My invention relates to sanitary chairs, 10 primarily for the use of small children and is adapted to enable them to be trained to answer the calls of nature without constant attention from nurse or mother.

The objects of my invention are to make 15 a sanitary chair which can be constructed and sold at a reasonable cost and which will efficiently assist the mother or nurse in training the infant child to answer the calls of nature at regular intervals; and which 20 will comfortably and safely support the child without constant attention. It is a further object to provide such a chair which may be adapted to the use of the child as it gets older, or adjusted for the use of children 25 of different ages. I accomplish these objects; by making a chair with a back of deeply curved, substantially semi-cylindrical cross section integral with and curving smoothly and regularly into a seat, also of 30 curved cross section which seat terminates in two separated leg supports, the whole adapted to smoothly fit the back and legs of the child and support it comfortably yet securely either in a recumbent or upright 35 position, by providing the back and the leg supports with straps or other fastenings to hold the child securely yet not tightly in place; and further by supporting the back and seat adjustably in a frame so that the 40 inclination of the back may be changed from substantially a reclining position for the youngest infant to an upright position for an older child.

The detailed way in which these objects 45 are accomplished is more clearly shown in the accompanying drawings in which,

Figure 1 is a sectional side elevation taken on the center line;

Fig. 2 is a plan view;

Fig. 3 is an end elevation;

Fig. 4 is a side elevation showing a modified form of side frame, and

Fig. 5 is a detail.

Referring now to the drawings in which 55 the various parts are indicated by letters of reference. The chair consists of a back A

which is of a deeply curved cross section, preferably somewhat more than half of a hollow cylinder, and which may be held in shape by curved ribs A₁—A₂. At the right 60 hand in Fig. 1 of the drawing this back of curved cross section curves forward, forming a seat B, which seat is of similar cross section being in the case shown practically one quarter of a hollow sphere. This seat 65 B is provided with the necessary sanitary opening C, which may be the usual circular or oval one, but which preferably extends to the extreme front of the seat, dividing it into two parts or leg supports B₁—B₂ which 70 are a continuation of the seat B and preferably are curved downward at their outer ends. The sides of these leg supports are preferably turned upward to form a deeply curved or semi circular cross section adapt- 75 ed to fit and steady the child's legs. The said leg supports are practically at right angles to the back so that in connection with the back and the balance of the seat they form a chair member adapted admirably 80 to comfortably and safely support a young child in proper position for the calls of nature. These parts are of a material adapted to be shaped or formed as shown, and when so formed, to hold their shape, 85 so that the back, seat and leg supports are of fixed or permanent cross section and are in a fixed relation to each other. D—D are straps which may be used, if desired, to fasten the child in the chair. 90

The combined seat and back A—B, which forms a complete member of the sanitary chair, is preferably supported by a frame in which E—E₁ are legs braced by cross members or rounds F thus forming two 95 parallel frames which in turn are connected together and braced by cross rounds G—G. H is a cross round on which the back A rests and is hinged, or pivoted, giving a firm support but permitting adjustment of the 100 inclination of the back. At the opposite end of the back A, some means of adjustably supporting the back on the side frames must be provided, and for this purpose I show in Figs. 1—2 and 3, arms I hinged to the 105 back A, which arms carry a rod J which rests in a rack K, attached to the legs E₁, permitting that end of the back to be raised or lowered to adjust the inclination of the 110 back and seat member of the chair from a reclining to a sitting position or vice versa.

It will, of course, be evident that the

exact detail of the frame is unimportant so long as the seat and back member is firmly supported; and that the form of pivot or hinge is immaterial so long as it serves the purpose of permitting the adjusting of the back and seat members to various positions. The rack K, too need not be of the identical form shown so long as the combination permits the results outlined. In Fig. 4 I have shown a slightly different design of frame in which the legs E₁ are curved around the cross round H as a center, and racks K₁ curved to fit are placed on said legs. A rod L (Fig. 5) may be passed through the holes K₂ in the racks to support the back A. A₃ is a retainer fastened to the rib A₂ to lock the back against accidental upward movement.

It will further be noted that the seat and back member may be used independently of any frame, and may, in fact, be entirely separate and be supported on the lap of a person or otherwise as desired.

It will also be noted that eliminating the sanitary opening the chair is in itself a useful and comfortable article and it is distinctly understood that while in the drawing I have shown only that form with the opening that I distinctly reserve the right to make this member with a solid seat without opening as though I had separately shown same.

Having now fully described my invention, what I claim and desire to secure by Letters Patent in the United States is:—

1. As a sanitary chair member, a back and an integral seat permanently formed approximately at right angles to each other, said back and seat being each permanently formed of deeply curved cross section and

said seat having a sanitary opening dividing it into two parts, substantially as shown and described.

2. As a sanitary chair member, a back of a permanently formed deeply curved cross section, and an integral seat fixed approximately at right angles to each other, said seat being divided into two parts by a sanitary opening, each of said parts having their edges adjacent to said sanitary opening turned upward to form a leg support of curved cross section, substantially as shown and described.

3. As a sanitary chair member, a back and an integral seat approximately at right angles to each other, said back and seat being each of deeply curved cross section and said seat having an opening therethrough dividing it into two parts, each part terminating in a leg support of deeply curved cross section, and all the parts of said chair member, being permanently shaped and permanently fixed in their relation each to the other.

4. In a sanitary chair member, the combination with a back of deeply curved cross section, of an integral seat divided by a sanitary opening into two parts, each of said parts terminating in a leg support, of curved cross section, bent downward approximately at right angles to said seat, all of said parts being permanently shaped, and permanently fixed in their relation each to the other.

In testimony whereof, I have hereunto subscribed my name.

JOSEPH H. WEATHERFORD.
